[57] CLAIM

The ornamental design for a laptop computer, as shown and described.

DESCRIPTION

FIG. 1 is a front, right side perspective view of a laptop computer having its display housing closed;
FIG. 2 is a rear, left side perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top view thereof;
FIG. 8 is a bottom view thereof;
FIG. 9 is a front, right side perspective view of the laptop computer having its display housing opened; and,
FIG. 10 is a rear, left side perspective view of the laptop computer having its display housing opened.
The pattern is partially shown in the views for ease of illustration and it is understood to continue uniformly across each of the indicated surfaces and the logo is shown in broken lines for illustrative purposes only and forms no part of the claimed design.
